CLAIM

The ornamental design for a toiletry bag, as shown and described.

DESCRIPTION

FIG. 1 is a front view of a toiletry bag of the present invention when the bag is in a closed configuration.

FIG. 2 is a back view of the toiletry bag shown in FIG. 1.

FIG. 3 is a left view of the toiletry bag shown in FIG. 1.

FIG. 4 is a right view of the toiletry bag shown in FIG. 1.

FIG. 5 is a top view of the toiletry bag shown in FIG. 1; and,

FIG. 6 is a bottom view of the toiletry bag shown in FIG. 1. The broken line showing is included for the purpose of illustrating unclaimed subject matter and forms no part of the claimed design.
